UNITED STATES PATENT OFFICE.

JOHN TOLAND, OF BOSTON, MASSACHUSETTS.

FILTER.

SPECIFICATION forming part of Letters Patent No. 291,550, dated January 8, 1884.

Application filed August 1, 1883. (No model.)

To all whom it may concern:

Be it known that I, JOHN TOLAND, of Boston, in the county of Suffolk, of the Commonwealth of Massachusetts, have invented a new and useful Improvement in Filters; and I do hereby declare the same to be described in the following specification and represented in the accompanying drawings, of which—

Figure 1 is a longitudinal section, Fig. 2 a transverse section, and Fig. 3 an end elevation, of a filter embodying my invention, the nature of which is defined in the claim hereinafter presented. Fig. 4 is a transverse section on the line $x^1 y^1$ of Fig. 1. Fig. 5 is a transverse section on line $x^2 z^2$ of Fig. 1.

The improvement relates to the kind of filter described and represented in the United States Patent No. 248,897, granted November 1, 1881, to me. In the place of chambered two-way cocks, as employed in such filter, I now use two valves, which have their spindles extended through stuffing-boxes, and I have with each valve a chamber provided with two valve-seats, which open into passages arranged on opposite sides of each valve-chamber, and which communicate with the interior of the case of the filter. These valves, chambers, passages, and seats are in two separate chests, each of which is provided with one valve-chamber, two valve-seats, and two passages leading therefrom, all being substantially as hereinafter described.

In such drawings, A denotes the filter-case, which has within it four passages, u and u' , v and v' . Within the case, and near each end of it, is a partition, as shown at a and a' , it being of woven wire, suitably secured in place between two spiders, b c , by means of screws d , going through the said spiders and partition and screwed into ears e , projecting inward from the case. The said case between the woven-wire partition is to be charged or filled with a suitable filtering medium, matter, or matters—such as bone charcoal, for instance. The cylindrical case A is open at its opposite ends, and has removable heads f f' , adapted to such ends, and fastened in place therein by screws g . Furthermore, the case A has on opposite sides of it two projections, D, having flat seats h to receive and support two valve-chests,

F F, fastened to such seats by means of screws i , arranged as shown. In each valve-chest F there is a chamber, k , provided with two valve-seats, l m , which open into two lateral passages, n o , arranged in the chest, and communicate with the four passages u v u' v' in the interior of the case A. Furthermore, there is in such chamber k a single valve, p , adapted to move from one to the other of the two valve-seats of such chamber, and suitably connected with a spindle, q , arranged in a stuffing-box, r , and screwed into the neck s thereof, such spindle being furnished at its outer end with a hand-wheel, t . There is in the upper part of the valve-chamber k an induction-opening, w , the eduction-opening being shown at y in the lower end of the valve-chamber k of the lower valve-chest. If, now, we suppose water, under a head or pressure, to be let into the valve-chamber of the upper valve-chest, and the valve of such chest to be against the seat l , the seat m will be uncovered, and the water will rush through the passage o ; thence into the passage v ; thence into the space between the head f' and the partition a' ; thence through the filtering medium and the partition a , and into the space between the head f and said partition, out of which space it will escape, by the passage u' , into the passage n , and next through the valve-seat l of the lower valve-chest; thence into the lower valve-chamber, k , and out of its eduction-opening y , the valve p of such chest being against its seat m . Now, if the upper valve be drawn backward against the valve-seat m of the upper valve-chest, and the lower valve be forced forward against the valve-seat l of the lower valve-chest, the direction of movement of the water will be reversed—that is to say, the water will flow through the passage n into the passage u ; thence into the space between the head f' and the partition a' ; thence through the filtering medium, and into the space between the head f' and the partition a' ; thence into the passage v ; thence into the passage o , chamber k , and educt y . By closing the two valves on the seats l l or on the two seats m m , water will flow through the case A and the educt y without going through the filtering medium.

I claim—

The filter-case A, provided with the passages $u v u' v'$, the woven-wire partitions $a a'$, and the heads $f f'$, arranged as set forth, and
5 the valve-chests F F', secured to the case A at opposite ends, and each having the two opposite seats $l m$ at opposite sides of the chamber k , in combination with the solid reciprocating valves $p p$ and their operating-stems $q q$, each

valve p being arranged across the chamber k , 10 and adapted to alternately uncover or close one of the seats by being moved transversely across the chamber, as set forth.

JOHN TOLAND.
